UNITED STATES PATENT OFFICE.

WILLIAM M. THOMAS, OF LOS ANGELES, CALIFORNIA.

REINFORCED-CONCRETE BRIDGE CONSTRUCTION.

1,303,741.

Specification of Letters Patent. Patented May 13, 1919.

Application filed October 20, 1913, Serial No. 796,180. Renewed August 5, 1918. Serial No. 248,460.

To all whom it may concern:

Be it known that I, WILLIAM M. THOMAS, a citizen of the United States, residing at Los Angeles, in the county of Los Angeles and State of California, have invented a new and useful Reinforced-Concrete Bridge Construction, of which the following is a specification.

This invention relates to reinforced concrete bridges and particularly to the construction of the bridge floor and the supporting means therefor.

One object of the invention is to provide improved means for bracing and reinforcing the floor.

Another object of the invention is to provide improved means for forming the spandrel members whereby the floor is supported from the main arch ribs of the bridge.

Other objects of the invention will appear hereinafter.

The accompanying drawings illustrate embodiments of my invention, and referring thereto:

Figure 1 is a side elevation of a portion of a bridge embodying the invention.

Fig. 2 is a transverse section on line x^2-x^2 in Fig. 1.

Fig. 2^a, is a plan of a tightening joint for the reinforcing means.

Fig. 3 is a perspective of the hook members for supporting the horizontal struts of the spandrel members.

Fig. 4 is a perspective of the upper portion of a spandrel post.

Fig. 5 is a perspective view of the upper horizontal member or girder for connecting the upper ends of the spandrel post.

Fig. 6 is a plan view of a portion of the bridge.

Fig. 7 is a transverse section on line x^7-x^7 in Fig. 6.

Fig. 8 is a transverse section of a portion of the bridge floor.

Fig. 9 is a horizontal section on line x^9-x^9 in Fig. 7, with intermediate portions of the bridge floor broken away.

Fig. 10 is a vertical section of the bridge floor, showing the floor arches or panels and reinforcements in position before the grouting for bonding the same has been poured into position.

Figs. 11 and 12 show modifications of the means for attaching the cross struts to the arch ribs and spandrel posts.

Figs. 11^a and 12^a are perspectives of tie rods shown in Figs. 11 and 12.

Fig. 13 is a transverse section similar to Fig. 2, the cross strut being omitted.

The bridge comprises main arch ribs 1 and 60 having outstanding skew backs at their upper ends, spandrel posts 2 supported thereby, girders 3 supported by said spandrel posts, and a bridge floor supported by said girders. The main arch ribs 1 are preformed and reinforced in any suitable manner and the spandrel posts 2 are also preformed and temporarily mounted upon the arch ribs and then secured thereto by a molded joint. For each spandrel member formed by the spandrel posts and girder connected to the same, there is also preferably provided a lower horizontal member or strut 5 extending between the main arch ribs and secured thereto and to the spandrel posts. Said strut 5 is 70 preformed of reinforced concrete and is provided with metallic hooks 7 projecting therefrom at each end, said hooks being embedded at one end in the strut 5 and extending upwardly at their outer ends and adapted to 80 engage in loops or eyes 8 molded into the main arch rib 1, so that the strut 5 may be placed in position with its hook 7 engaging in the eye 8 and will be supported thereby during the construction. Said strut 5 is 85 further provided with longitudinally extending reinforcing rods 10 adapted to be connected to anchor rods 11 projecting from the main arch ribs 1. Any suitable means may be used for securing these rods together, for 90 example, as shown in Fig. 2^a, said rods may extend in opposite directions through an anchor plate 12, nuts 13 being screwed on said rods on opposite sides of said plate, so that by tightening said nuts, the plate 12 is 95 caused to exert tension on all of said rods, so as to give a tight horizontal connection between the main arch ribs and the strut 5.

The strut 5 is also provided with reinforcing rods 15 extending obliquely upward and connected by a plate 12' and nuts 13' to reinforcing rods 17 extending obliquely downward from the spandrel posts 2, the construction for the parts 12' and 13' being the same as above described for parts 12 and 13, see 105 Fig. 2^a. Each spandrel post 2 is provided at its lower end with a recess 18 at each side, the reinforcing rod 17 aforesaid, extending down through said recess and vertical reinforcing rods 20 extending down through the outer 110

- recess 18 and being connected by plates 12^a and nuts 13^a similar to plate 12 and nuts 13 above described, to reinforcing rods 21 projecting upward from the main arch rib.
- 5 When the main arch ribs 1, strut 5, and spandrel posts 2 have been connected by the reinforcing members 10, 11, 15, 17, 20, and 21, as above described, and thereby rigidly secured in position, mold boards are placed 10 in position so as to inclose the recesses 18 and the space 24 between the strut 5 and the adjacent faces of the main arch rib and spandrel post, and the cement or grouting is run or filled into such recesses 18 and space 15 24 to form concrete cement bonds 22 and 23 between the preformed members 1, 2, and 5, uniting the same into a unitary monolithic structure.
- 20 The spandrel posts 2 are provided at their upper ends with rabbets forming vertical faces 26 and horizontal bearing faces or shoulders 27 and the girders 3 are provided at their ends with bearing faces 23 adapted to rest on said shoulders. Metal rods 28 extending obliquely upward from said shoulders are adapted to extend into recesses or sockets 29 in said girders when the latter are in position and the said girders are provided with downwardly extending metal rods or pins 29' adapted to engage in recesses 30 in the spandrel posts extending obliquely downward from said shoulders 27. The ends of the girders 3 are provided with recesses 32 in their upper faces through which extend 25 horizontal reinforcing rods 33. Horizontal rods 34 extend from the upper part of each spandrel post and are connected to said horizontal rods 33 of the girders by plates 12^b and nuts 13^b similar to plate 12 and nuts 13 above described. The girders are so proportioned that when in position on the shoulders 27 a space 36 will be left between the end of each girder and the vertical face 26 of the spandrel post and suitable mold boards 45 being put in position, these spaces 36 and the recesses 29 aforesaid are filled with grouting or cement, so as to bond the girders onto the spandrel posts to form a unitary monolithic structure therewith.
- 50 The bridge floor is composed of a plurality of preformed floor blocks or members 40 resting on the girders 3 and concrete or cement uniting said floor members to one another and to the girders. Each of these 55 members 40 is formed as a cantilever, and they are placed on the girders in such position as to form arches and to leave spaces or channels 42 between their upper ends, extending longitudinally of the bridge, and 60 said members 40 are spaced apart longitudinally so as to form channels 43 extending transversely of the bridge. Longitudinal reinforcing bars 44 extend in said longitudinal channels 42 and transverse reinforcing 65 bars 45 extend in said transverse channels 43.
- Reinforcing members 46 embedded in the girders 3 extend upwardly into the longitudinal channels 42 and are bent around the reinforcing rods 44. When the parts are in position, as above described, cement or 70 grouting is run into the longitudinal and transverse channels 42 and 43 aforesaid, and fills the said channels as well as the spaces 43 between the members 40 directly over the girders, the cement being continued or built 75 up on top of the members 40 to any desired height to form the floor. It will be understood that in the spaces between the girders the bottoms of the longitudinal channels 42 are closed by mold boards so that the cement 80 at these parts only fills said channels so as to form with the members 40 complete arches supported on the girders.
- Each of the floor members 40 is provided with reinforcing rods 50 in its lower or central portion extending longitudinally of the bridge, these rods projecting into and being embedded in the concrete poured into the transverse channels 43. The outside floor member 40' at each side of the bridge is also 85 provided with reinforcing rods 50' at its lower portion, extending longitudinally of the bridge, and embedded in the cement between the panels. At the outer side of each of these outside panels are provided upper 90 reinforcing rods 51 and lower reinforcing rods 52, extending longitudinally of the bridge, and tied to the floor body by lower tie rods 53, and stirrup means 54. Tie rods 53 are connected by plates 55 and nuts 56, 100 similar to the plates 12 and nuts 13 above described, to rods 57, which are embedded in floor members 40. Stirrup means 54 are embedded in the floor member or blocks 40' and are preferably formed by bending a rod in 105 zig zag shape, said rod being looped at its outer ends over the longitudinal rods 51 and 52 and the bends or loops of the rod being embedded within said floor members as shown at 61. At certain points where a special bracing effect is desired, for example, at the midlength of each floor member 40', the loop or bend of the zig zag rod is extended into the longitudinal channel 42 as shown at 58. The zig zag rod 54 may be bent 110 up and down alternately over the upper and lower rods, 51 and 52, as shown, or it may be bent over only one of the rods so as to lie in one plane. The floor members 40 adjacent these outside members 40' are provided 115 with metallic anchor rods 62 embedded therein and projecting therefrom and turned down as shown at 63 to extend through the loops or bights 58 of the reinforcing rods or stirrups 54. These metallic connections 58, 120 63 are embedded in the cement filling the longitudinal passages 42. Outside facings 59 of concrete cover and embed the longitudinal rods 51 and 52.
- As shown in Fig. 11, the main arch rib 1 125
- 130

may be provided with metal tie rods 65, looped around vertical reinforcing 21 in the main arch rib and embedded in said rib, said rods 65 extending obliquely downward from 5 the main arch ribs and into recess 67 in struts 5 and being bent laterally at their lower ends, as shown at 65', so that when the cementitious bond 68 is molded in position it embeds the bent portion 65' and connects the 10 same to the strut.

The strut may be provided with tie rods 70 as shown in Fig. 12, extending obliquely upward and over the arch rib, and bent around the vertical reinforcing rods 21 above 15 the arch ribs, these tie rods being embedded in the cement bond 22, filling the outside recess 18 of the spandrel post.

In some cases the transverse struts for the spandrel members may be omitted. Thus as 20 shown in Fig. 13, arch ribs, spandrel posts, and girders may be constructed and connected as above described without the use of a transverse strut.

What I claim is:

- 25 1. In combination, main arch ribs provided with upwardly extending and transversely extending reinforcing rods, spandrel posts having their lower ends resting on the main arch ribs and recessed at their inner 30 and outer faces adjacent the upper faces of the main arch ribs, reinforcing rods in the posts connected in the outer recesses to the upwardly extending rods of the main arch ribs, other reinforcing rods in the posts extending obliquely downwardly and inwardly 35 from the inner recesses, a strut extending transversely between the main arch ribs and having its ends spaced apart from the side faces of said ribs, reinforcing rods in the 40 strut projecting from the ends thereof and connected in the spaces to the transversely extending rods of the posts, other reinforcing rods in the strut projecting obliquely upward and outward from the ends thereof 45 and connected in the spaces to the downwardly and inwardly projecting ends of the rods of the posts, and cement bonds filling in the recesses and filling in the spaces between the ribs and ends of the strut.
- 50 2. In combination, main arch ribs provided with upwardly extending and transversely extending reinforcing rods, the transversely extending rods having loops,

spandrel posts having their lower ends resting on the main arch ribs and recessed at 55 their inner and outer faces adjacent the upper faces of the main arch ribs, reinforcing rods in the posts connected in the outer recesses to the upwardly extending rods of the main arch ribs, other reinforcing rods in the 60 posts extending obliquely downwardly and inwardly from the inner recesses, a strut extending transversely between the main arch ribs and having its ends spaced apart from the side faces of said ribs, reinforcing rods 65 in the strut projecting from the ends thereof and connected in the spaces by hooks to the loops of the transversely extending rods of the posts, other reinforcing rods in the strut projecting obliquely upward and outward from the ends thereof and connected in the spaces to the downwardly and inwardly projecting ends of the rods of the posts, and cement bonds filling in the recesses and filling in the spaces between the ribs and ends of the strut.

3. In combination, spandrel posts having shoulders and having outstanding skewbacks at their upper ends, there being recesses in the shoulders, a girder extending 80 transversely between the skewbacks and resting on the shoulders and having its ends spaced apart from the inner faces of the skewbacks, the ends of the girder being provided with recesses in its upper and lower faces, reinforcing rods extending upward from the shoulders into the lower recesses, reinforcing rods extending transversely from the inner faces of the skewbacks, reinforcing rods in the girder extending 85 through the upper recesses thereof and connected in said recesses to the transversely extending rods of the skewbacks, other reinforcing rods in the girder projecting obliquely downward and outward and 90 seated in the recesses of the shoulders, and cement bonds filling in the recesses and filling in the spaces between the skewbacks and ends of the girder.

In testimony whereof, I have hereunto set 100 my hand at Los Angeles, California, this 9th day of October, 1913.

WILLIAM M. THOMAS.

In presence of—

ARTHUR P. KNIGHT,
LORRAINE E. DURROW.
